FLAG OR SIMILAR MOUNTING FOR AERIALS

James C. Shepherd, Kansas City, Mo.

Application August 21, 1941, Serial No. 407,761

6 Claims. (Cl. 116—173)

This invention relates to a mounting for attachment of a flag, pennant or banner to an automobile aerial, and has for its principal object to provide a simple and inexpensive device of this character which is readily applied and removed, and which does not interfere with telescoping of the aerial sections.

Another object of the invention is to provide a flag mounting formed of spring wire or equivalent material arranged to effect a frictional grip upon an aerial incidental to application thereof so that it may be located in any selected position thereon.

Further objects of the invention are to provide a flag mounting applicable to inclined aerials; to provide a flag mounting with means for ready attachment of a flag or other banner so that it is displayed at the desired angle without fouling on the aerial or mounting; and to provide a mounting that is adjustable for accommodating flags of different depth.

In accomplishing these and other objects of the invention, as hereinafter pointed out, I have provided improved structure, the preferred forms of which are illustrated in the accompanying drawing, wherein:

Fig. 1 is a perspective view of a flag mounting constructed in accordance with the present invention and showing application thereof to an automobile aerial.

Fig. 2 is a side elevational view of the flag mounting as applied to the aerial.

Fig. 3 is a rear elevational view of the flag mounting prior to application of a flag.

Fig. 4 is a side elevational view of a modified form of the invention, particularly adapted for inclined aerials.

Fig. 5 is a side elevational view of a further modified form of flag mounting, the staff portion of which is adjustable for flags of different depth.

Fig. 6 is a perspective view of the upper section of the modified form of mounting shown in Fig. 5.

Fig. 7 is a perspective view of one of the links for attaching a flag or other banner to the mounting.

Referring more in detail to the drawing:

I designates a flag or like mounting constructed in accordance with the present invention. In the illustrated instance the mounting 1 is formed of spring wire to provide a resilient staff portion 2 of slightly greater length than the depth of the flag or banner 3 supported thereby, as later described. The wire at the ends of the staff portion is bent to form eyes 4 and 5 and the ends of the wire continue substantially in the plane of the staff after formation of the eyes. The terminal

end 6 of the upper eye 4 is bent laterally as at 7 to provide a short angularly extending bar portion 8, terminating in a bend 9 forming a bar portion 10 extending in the opposite direction and terminating in the extended axis of the staff 2 in a reverse bend 11 forming a downwardly extending angular bar portion 12, parallel with the portion 2 and terminating in an angular bend 13 forming a bar portion 14 substantially parallel with the bar portion 10 and which terminates in a reverse bend 15 forming a terminal bar portion 16 substantially coextensive with the bar portion 8, as shown in Figs. 2 and 3. The bends thus form a parallelogram-shaped head portion with the bends 11 and 15 forming seats 17 and 18 curved to engage frictionally the aerial 19 on which the mounting is to be attached, as later described. The end of the wire forming the lower eye 5 extends a short distance in a plane parallel with the axis of the staff and terminates in a right angular bend 20, which, in turn, is bent to form a hook 21 located in a plane extending transversely of the axis of the staff 2.

The flag or banner 3 may be of any conventional design and is attached to the eyes 4 and 5 by means of safety pins or links 22, each of substantially elongated, loop-shaped form having rounded ends 23—24, a side bar 25 and connecting bars 26 and 27. The bar portion 26 terminates in a hook 28 which engages the free end of the bar 27, as shown in Fig. 7. The eyes 4 and 5 are spaced apart a sufficient distance relatively to the depth of the flag so that the links 22 are positioned at an angle for maintaining required spread of the flag.

In attaching the flag or banner 3, the bar 27 is disengaged from the hook 28 and the end is extended through the fabric of the flag in the corner thereof, after which the hook end 28 is passed through the eye 4. The bar 27 is then reengaged with the hook 28 to complete attachment of the upper corner of the flag. The lower corner of the flag is secured in a similar manner to the eye 5.

In applying the device to the aerial, the parallelogram shaped head is passed over the front of the aerial with the eyes in trailing position. The staff portion of the device is then swung laterally so that the aerial is caused to pass between the end 16 and the bar portion 8 of the head until the terminal end 16 passes the mast. The staff portion is then swung rearwardly until the end 16 clears the aerial, whereupon the staff portion is moved toward parallel relation with the aerial which engages the seat 17 with the front portion of the aerial, and the seat 15 with

the rear portion of the aerial, as shown in Fig. 2, and placing the head in a bind on the aerial. Then when the lower free end of the staff is moved toward the aerial to engage the hook 21 therewith, a bow is imparted in the staff portion of the mounting, exerting a spring action therein, causing the seats 15 and 17 to engage frictionally the aerial on the respective sides thereof and to retain the hook in engagement with the aerial as shown in Fig. 2. The mounting is thus retained in the applied position by friction imparted incidental to slight bowing of the staff 2 so that it is retained in any selected elevation relative to the aerial.

If it is desired to change the position of the mounting on the aerial, this is readily effected by releasing the hook end 21 to relieve tension on the head portion, whereupon the wire may be freely moved along the aerial. When the hook is again engaged, the spring action of the staff will retain the device in its newly selected position.

Should the flag be attached to the upper section of the aerial and it is desired to collapse the aerial, the upper section carrying the flag is merely slid into the lower section, and when the hook end engages the upper end of the next lower section of the aerial, it slides freely there-over.

In order that the flag may be displayed at the proper angle on inclined aerials, as shown in Fig. 4, the lower end of the staff section is provided with a laterally extending arm 29, of sufficient length to maintain the staff in perpendicular position when the hook 30 on the terminal end of the arm is engaged with the mast, as shown in Fig. 4.

In order that flags of various size may be applied to the device, I have shown a modified form of staff in Figs. 5 and 6, composed of upper and lower sections 31 and 32, the upper section having an eye 33 similar to the eye 4, and the lower section having an eye 34 similar to the eye 5. The ends of the sections overlap and are provided with a series of crimps 35 and 36, the crimps on one section being engaged by a hook 37 on the other section so that the desired space may be maintained between the eyes 33 and 34. When the device is applied, the spring action effected in the staff section retains the hooks 37 in engagement with the selective crimps to maintain the desired length of staff.

From the foregoing it is obvious that I have provided a flag mounting or the like that is of simple, inexpensive construction, and which is readily attached and adjusted upon an automobile aerial.

While I have particularly described my improved mounting as applied to an aerial, it is obvious that it may be applied to any taut rope, wire, or rod, and used for attaching advertising banners, various markers, or the like, without departing from the spirit of the invention.

What I claim and desire to secure by Letters Patent is:

1. In combination with an inclined aerial, a

staff formed of spring material and having a head adapted for frictionally engaging the aerial and having an arm at its lower end terminating in a hook engaging the aerial and cooperating with the head in retaining the staff in vertical position, said head being shaped to space the hook from the aerial when only the head is engaged whereby a spring action is imparted in the staff when the hook is engaged with the aerial.

5 with the head in retaining the staff in vertical position, said head being shaped to space the hook from the aerial when only the head is engaged whereby a spring action is imparted in the staff when the hook is engaged with the aerial.

10 2. A mounting of the character described including, a section having a head adapted to frictionally engage an aerial, a lower section having means adapted to engage the aerial, said sections having juxtaposed crimped portions, and means

15 on the respective sections to engage the crimps of the other section for adjustably connecting said sections.

3. A flag mounting of the character described including, a spring metal staff comprising adjustably connected sections, one of said sections having a head adapted to frictionally engage an aerial with said staff projecting outwardly from the aerial at an angle when only the head is engaged with the aerial, and a hook on the other section adapted to engage the aerial to cooperate with the head in imparting a spring action

in said staff.

4. A flag mounting for an aerial including, a staff formed of substantially spring metal, means on the respective ends of the staff arranged to frictionally engage the aerial and having shape to impart a slight bow in the staff when said aerial engaging means is engaged with the aerial to enhance frictional contact of said engaging means, and spaced means on the staff intermediate said aerial engaging means for attaching a flag.

5. A flag mounting for an aerial including, a
spring wire staff, a head on one end of the staff
40 and having aerial engaging portions on opposite
sides thereof and spaced from each other in the
longitudinal direction of the staff to cause the
opposite end of the staff to extend at an angle
relatively to the aerial when said portions are
45 engaged with the aerial, a hook on the opposite
end of the staff to engage the aerial and impart
a slight bow in the staff when said end of the
staff is brought toward the aerial and the hook
engaged with the aerial, and spaced eyes in the
50 staff intermediate said head and hook for at-
taching a flag.

6. A flag mounting for an aerial including, a spring wire staff, a substantially rectangular head formed on the staff by bending said wire and arranged with a diagonal thereof extending substantially in the longitudinal direction of the staff whereby the corners of said head form seats for engaging opposite sides of an aerial with the staff extending outwardly at an angle to the aerial when only the head is engaged with the aerial, a hook formed on the other end of the wire to engage said aerial for effecting a spring action in the staff after the hook is engaged with the aerial, and means on the staff intermediate said hook and head to attach a flag.

JAMES C. SHEPHERD.
